CLAIM

The ornamental design for a reader and array, as shown and described.

DESCRIPTION

FIG. 1 is a perspective view of the reader and array with the flaps closed in accordance with an embodiment of the design;

FIG. 2 is another perspective view of the reader and array with the flaps closed in accordance with an embodiment of the design;

FIG. 3 is a top view of the reader and array with the flaps closed in accordance with an embodiment of the design;
FIG. 4 is a bottom view of the reader and array with the flaps closed in accordance with an embodiment of the design;
FIG. 5 is a side view of the reader and array with the flaps closed in accordance with an embodiment of the design;
FIG. 6 is another side view of the reader and array on the side opposite from that of FIG. 5 with the flaps closed in accordance with an embodiment of the design;

FIG. 7 is an end view of the reader and array with the flaps closed in accordance with an embodiment of the design;
FIG. 8 is a perspective view of the reader and array with the flaps open in accordance with an embodiment of the design;
FIG. 9 is another perspective view of the reader and array with the flaps open in accordance with an embodiment of the design;

FIG. 10 is a bottom view of the reader and array with the flaps open in accordance with an embodiment of the design;
FIG. 11 is a top view of the reader and array with the flaps open in accordance with an embodiment of the design;
FIG. 12 is a side view of the reader and array with the flaps open in accordance with an embodiment of the design;
FIG. 13 is an end view of the reader and array with the flaps open in accordance with an embodiment of the design; and,
FIG. 14 is another side view of the reader and array opposite of that of FIG. 12 with the flaps open in accordance with an embodiment of the design.
